(57) **CLAIM**

(21) Appl. No.: **29/270,130**

The ornamental design for a combination magnifier and housing for tweezer arms, as shown and described.

(22) Filed: **Dec. 15, 2006**

DESCRIPTION

(51) **LOC (8) Cl.** **16-06**

FIG. 1 is a perspective view of a combination magnifier and housing for tweezer arms showing our new design;

(52) **U.S. Cl.** **D16/135**

FIG. 2 is a top plan view thereof;

(58) **Field of Classification Search** D16/130,

FIG. 3 is a bottom plan view thereof;

D16/135; 359/802-805, 808-809, 810-811;

FIG. 4 is a first end elevational view thereof;

606/210-211; D28/55; D7/391, 664; 294/55;

FIG. 5 is a second end elevational view thereof;

294/99.2; 30/120.3; D24/143; 452/

FIG. 6 is a right side elevational view thereof;

See application file for complete search history.

FIG. 7 is a left side elevational view thereof; and,

(56) **References Cited**

FIG. 8 is a perspective view of the combination magnifier and housing for tweezer arms in an exemplary “open” position.
